WILHELM DIERKS, OF OSNABRUCK, GERMANY

STIRRER MECHANISM

Application filed February 25, 1930, Serial No. 431,223, and in Germany March 23, 1929.

This invention relates to a stirring device including a stirring blade mounted for movement about the axis of oscillation of a trough of substantially half-round section and has 5 for its object to provide a construction permitting a large throw of the stirring blade and easy and convenient tilting of the trough.

Particularly the necessity for tilting the 10 trough heretofore involved great difficulties in the practical operation of such devices or has been a source of trouble to the attendant. When it was desired to tilt a trough with 15 mechanically operated stirring mechanism about the axis of oscillation it was necessary first to uncouple the stirring blades from the actuating device so that they would not abut against any parts of the trough being tilted but could participate in the tilting 20 movement. Similar roundabout methods had to be followed in resetting the actuating mechanism after completion of the tilting operation. Heretofore it was necessary 25 to provide a latch device which prevented tilting of the trough during oscillation of the stirring blades and conversely prevented the running of the stirring mechanism while the trough was being tilted.

These drawbacks are overcome if the 30 trough can be tilted free from hindrance also during the movement of the stirring blades. It has heretofore been proposed therefore to attach the stirring actuating mechanism directly on to the side of the trough so that it could be rocked together 35 with the trough. Such a construction, however, renders the trough too unhandy and also the cleaning of the trough and the lubrication of the stirrer actuating mechanism 40 present fresh difficulties.

All these drawbacks are avoided and the 45 object above set forth realized in simple manner by the construction according to the present invention as hereinafter described and illustrated by way of example in the accompanying drawing.

In the drawing Fig. 1 is an end elevation 50 of the trough and stirrer mechanism, Fig. 2 a longitudinal section and

Figs. 3 and 4 detail views showing modifications.

Referring to the drawing, a trough *a*, Figs. 1 and 2, of substantially half-round section suspended so as to be free to oscillate in standards *s*¹ and *s*² is provided at the driving end with a hollow shaft *b* through which is guided the shaft *c* of a stirring blade *d*. The actuation of said shaft *c* is effected by a crank mechanism by way of a bevel pinion *f* which is rotatably mounted on a lever arm or spindle *i* attached to a boss *j* surrounds and is free to rock on the shaft *c*. The pinion *f* meshes with a bevel sector *h* secured to the stirrer shaft *c* and also with a bevel gear *g* rotatable about the shaft *c*, the said gear *g* being operatively connected by way of a bevel pinion *k* rotatably mounted on a stud carried by the machine frame, with a bevel sector *l* secured 70 to the shaft *b*.

On tilting the trough *a* by hand directly or by means of the worm *p* and segment *q*, whether the crank mechanism is in movement or not, the bevel sector *h* fast on the shaft *c* is rocked by transmission of the tilting movement by way of the sector *l*, pinion *k* and bevel gears *g* and *f* through the same angle and in the same direction as the trough.

The stirring movement or the oscillation of the shaft *c* is effected by the crank mechanism *e* actuated by the belt-pulley *m* from the crank pin *n* of which mechanism a connecting rod *o* is operatively connected to the free end of the spindle *i*. The bevel pinion *f* rolls during the crank throw on the gear *g* through an angle depending on the crank throw and shifts the segment *h* through twice said angle, followed by a movement of equal extent on the return throw. This duplication of the angle of rotation effected by the crank in the transmission to the stirring mechanism is of particular importance, and renders possible for example the giving to the stirrer *d* a throw 180° or more.

If during the crank movement tilting movement of the trough is initiated, the pinion *f* is given by the movement of the otherwise sta- 100

tionary gear g an additional turning movement, or its actual turning movement is diminished, depending on the direction of tilt; that is, differential movements are produced.

- 5 As the result the stirrer d in the trough a is always confined to predetermined paths and always sweeps the same portions of the wall of the trough in whatever position the trough a may be located.
- 10 In Figs. 3 and 4 it is shown that instead of bevel gears for actuating the stirrer mechanism there may also be used spur gears. In the construction according to Fig. 3 there are used two internally toothed gears or segments
- 15 l' and h' in place of the members l and h , and a spur wheel g' in place of the bevel gear g . In the construction according to Fig. 4 a single internally toothed member g^2 is substituted for the member g and two spur gear
- 20 segments l^2 and h^2 are substituted for l and h . In both constructions (Figs. 3 and 4) instead of the spindle i (Fig. 2) on which the pinion f turns, there is provided a rock lever r to which is secured a pin to carry the gear f'
- 25 or f^2 .

I claim:—

1. The combination of a trough of substantially half-round section tiltable about its axis on a hollow shaft, of a stirrer mounted for
- 30 rocking movement about said axis, a stirrer shaft aligned with said axis for actuating said stirrer, and stirrer shaft actuating mechanism including an actuating pinion, and differential gearing co-operative with said pinion and interposed between said shafts, said gearing comprising a gear member freely rotatable about said axis and meshing with said pinion, a gear member fixed to rotate with said trough and also meshing with said pinion, and a
- 35 pinion rotatable about a fixed axis and engaged with both said gear members.

2. The combination of a trough of substantially half-round section tiltable about its axis, of a stirrer mounted for rocking movement about said axis, a hollow shaft fixed to said trough in the line of said axis, a stirrer shaft extending through said hollow shaft, and stirrer actuating mechanism including an actuating pinion and differential gearing comprising a set of gears co-operative with said pinion and interposed between said shafts.

In testimony whereof I have signed my name to this specification.

55 WILHELM DIERKS.
